UNITED STATES PATENT OFFICE

DONALD D. HERON, OF PITTSBURGH, PENNSYLVANIA

TOOTH EXERCISER

Application filed April 13, 1929. Serial No. 354,775.

This invention relates to dental appliances and more in particular to devices for exercising the teeth and massaging the gums.

One of the principal objects of this invention is to provide a device for exercising the teeth, by mastication, to prevent the decay thereof, to strengthen them and also to harden the gums. A further object is to provide a tooth exerciser which will carry its beneficial effects to the roots of the teeth 10 as well as to the visible parts thereof. Another object of this invention is to provide a tooth exercising device which may be readily applied to the handle of any commercial type of tooth brush, thereby offering 15 a better hold for the handle and being in the most advantageous position to suggest its use after each tooth-cleaning operation. Still another object is to provide a device which is of very simple construction and 20 use, and which can be manufactured at low cost. Additional features and advantages of this invention will appear from the following description considered in connection with the accompanying drawings which 25 form a part of this application.

In the drawings:

Fig. 1 is a view illustrating my device as applied to the handle of a tooth brush.

Fig. 2 is a side elevation of the simplest 30 embodiment of my invention.

Fig. 3 is an end view of Fig. 2.

Fig. 4 is a side elevation of a modified construction of the tooth exerciser.

Fig. 5 is a similar view showing another 35 modification.

Fig. 6 is an end view of Fig. 5.

Fig. 7 shows still another modification of the invention.

Fig. 8 is a plan view of the bottom side 40 of Fig. 7.

It is now a generally recognized fact in dentistry that the lack of sufficient exercise of the teeth, by mastication, is one of the primary causes of many dental afflictions, 45 such as decay, brittleness, pyorrhea of the gums, etc., etc. The bad effects of lack of exercise of the teeth are especially accentuated in cases of malposition or malocclusion of the teeth, since the latter can not be prop- 50 erly exercised without causing a consider-

able amount of discomfort or pain to the person so afflicted.

By proper exercise of the teeth, there is developed in the tissues thereof greatly increased hardness and resistance against decay, and pyorrheal conditions of the gums 55 are practically prevented. Also, by keeping the teeth properly exercised, the possibilities of abscess formation around the roots of the teeth are greatly reduced.

The use of my tooth exerciser by children 60 is very beneficial, since it is essential that the deciduous teeth be retained in good condition and as long as possible, so that the permanent teeth, when they erupt, may retain their proper position in the mouth. Succinctly stated, the tooth brush takes care of 65 the exterior of the teeth only, whereas the tooth exerciser of my invention benefits the inner structure and the roots of the teeth.

Referring to Figs. 1, 2 and 3, the simplest 70 form of my invention comprises a prismatic body portion 1 made of resilient, non absorbent material, such as rubber, of suitable consistency to yieldingly resist the biting action of the teeth, and of suitable length to 75 be engaged by several teeth at a time.

The body portion has a straight top 2 and an inwardly arcuate bottom 3 which latter is used for massaging the teeth and the 80 gums by combined longitudinal and transverse movements. The large, substantially parallel sides 4 and 5 are the biting surfaces and they are concaved, as at 6, to afford a better grip for the teeth and prevent the exerciser from slipping out from between 85 the teeth. As shown, the concave portions are straight at the top and below they follow an arcuate outline concentric with the bottom 3. Near the top is located a substantially rectangular aperture 7 extending 90 longitudinally of the body and adapted to receive the outer end of the handle of the tooth brush B, Fig. 1. The tooth exerciser is held on the handle by its own elasticity, 95 no cementing or gluing means being used, and it may be readily applied onto another brush, whenever required. Below the aperture 7 there is another longitudinal aperture 8, the purpose of which is to lend more 100

resiliency to the bitten portion of the exerciser.

The modified construction shown in Fig. 4 differs from the one just described in that 5 transverse corrugations 9 are provided on the bottom 3 to increase the massaging action of the device.

In the modification shown in Fig. 5, the 10 front end 10 of the tooth exerciser has been bevelled and rounded off at the top, to afford better access to the teeth and gums in the back of the mouth. Aside from this difference, the construction is identical with the one already described.

15 Instead of using transverse corrugations, as shown in Figs. 4 and 5, the bottom side of the device may be provided with teats 11, or other protuberances, disposed preferably in staggered relation, for massaging 20 the teeth and gums. This is illustrated in Figs. 7 and 8.

As will be understood, the exercising of 25 the teeth consists in taking the exerciser between the teeth and biting thereon repeatedly and then shifting the position of the exerciser until all teeth have been properly treated. The massaging action consists in rubbing the arcuate portion 3 of the exerciser over the teeth and gums by describing 30 a combined longitudinal and transversal movement of the device. This increases the circulation of the blood and also promotes the flow of saliva.

From the above description, it is thought 35 that a clear and comprehensive understanding of the construction, operation and advantages of my invention may be had, and while I have shown and described my invention as embodying specific structures or 40 forms, I desire to reserve the right to make such changes in the device as do not depart from the spirit and scope of the appended claim.

I claim:—

45 A tooth exerciser comprising a prismatic body portion made of resilient non-absorbent material having two concave, smooth and substantially parallel sides adapted to be engaged simultaneously by the teeth, and 50 an inwardly arcuate bottom portion; said body portion having two longitudinal apertures, one of said apertures being adapted to resiliently secure and closely engage a handle therein and the other aperture serving 55 to increase the resiliency of said exerciser.

In testimony whereof I affix my signature.
DONALD D. HERON.
